UNITED STATES PATENT OFFICE.

RALPH B. HOSNER, OF SAN FRANCISCO, CALIFORNIA.

SOFA-BED.

1,398,324.

Specification of Letters Patent. Patented Nov. 29, 1921.

Application filed February 8, 1919. Serial No. 275,855.

To all whom it may concern:

Be it known that I, RALPH B. HOSNER, a citizen of the United States, and a resident of the city and county of San Francisco and State of California, have invented a new and useful Sofa-Bed, of which the following is a specification.

My invention relates to a combination sofa and bed.

10 An object of the invention is to provide a sofa capable of being opened to provide a double bed.

Another object of the invention is to provide a sofa bed in which the bed portion 15 may be unfolded and detached from the rest of the apparatus.

The invention possesses other features of advantage, some of which, with the foregoing, will be set forth in the following description of the preferred form of my invention which is illustrated in the drawings accompanying and forming part of the specifications. It is to be understood that I do not limit myself to the showing made 25 by the said drawings and description, as I may adopt variations of the preferred form within the scope of my invention as set forth in the claims.

Referring to the drawings:

30 Figure 1 is a vertical sectional view through the sofa bed of my invention when the apparatus is folded to provide a sofa.

Fig. 2 is a vertical sectional view through the sofa bed when the bed frames are extended to provide a double bed.

Fig. 3 is a side elevation of the bed frame when detached from the rest of the apparatus.

My sofa bed comprises a main supporting 40 frame or housing 2, in which the seat frame 3, back frame 4 and bed frame sections 5 and 6 are appropriately mounted. The bed frame sections 5 and 6 are pivotally connected together by a knuckle joint 7. The 45 section 5 is provided with lugs 8 adapted to pivotally seat in sockets 9 fixed on the sides of the housing. The outer end of bed frame section 6 is provided at each side with a leg 11 connected by link 12 with section 5 so 50 that the extension of the leg accompanies the unfolding of the bed frame. An independently controlled leg 13 is also pivoted on each side of the section 5 so that if desired the bed frame may be lifted clear of 55 the housing and set up as a bed independent thereof.

A mattress 14 is disposed upon the bed frame and when the sections fold into the housing the mattress folds on the outside of the sections. A bed frame long enough for 60 the extended mattress is longer than needed for the mattress when folded on the outside of the folded sections and so the two ends of the bed frame are provided with movable parts which are extended when the bed 65 is unfolded and retracted when the bed is folded.

At the head end of section 5 an extensible section 16 is slidably arranged on pins 17. A head board 18 is pivoted to the extensible 70 section and is adapted to turn down upon the mattress to help secure it on the frame. A spring 19 is so arranged as to retain the head board either in the upright or folded position. The foot end of section 6 is similarly provided with an extensible section 21 and pivoted foot board 22 retained by spring 23. A stop 24 is fixed on each side of the housing to support the bed frame when folded within the housing. 80

The seat frame 3 is pivotally attached to the housing by pins 26 passing through the arms 27 fixed on the frame. The form of the arms and the position of the pins are such that the seat frame may be thrown up 85 from the normal position shown in Fig. 1 to permit the bed frame to be extended as shown in Fig. 2. A link 28 provided with a handle 29 and adapted to engage a fixed stop 31 provides means for retaining the 90 seat frame in the raised position. The back frame 4 is provided with an arm 32 on each end, formed with a slot 33 engaging spaced rollers 34 and 35, so that the back frame is vertically slidable in the housing, and the 95 lower edge of the frame is provided with shoes 36 which rest on the arms 27 so that the back frame rises and falls with the movement of the seat frame.

With the bed frame in the extended position, as shown in Fig. 2, the upwardly opening knuckle joint 7 retains the sections in horizontal alinement. In folding into the housing the section 5 inverts drawing the non-invertible section 6 in on top of it. 105 The under surfaces of the two sections, thus fold together, with the mattress on the outside of the sections.

I claim:

1. In a sofa bed, a housing, a bed frame 110 comprising pivoted sections adapted to be folded within said housing, a mattress asso-

ciated with said bed frame sections, a section slidably arranged on the end of each bed frame section to support the ends of the mattress, a board pivoted to each slideable section and forming head and foot boards when the bed frame is extended and adapted to be turned over upon the mattress to hold it upon the bed frame when the latter is folded within the housing, and means for resiliently retaining the boards in either position.

2. A bed structure having a mattress frame, a section slidably mounted on an end of the frame, and a board foldably mounted on said section to form, in one position, a foot or head board and adapted to fold over the mattress.

3. A bed structure having a mattress

frame, an end section slidably mounted on the frame to be extended therealong, and a spring controlled foot board foldably attached to the sliding section.

4. A bed structure having a mattress frame, an end section having a pin and slot connection with the frame so that said section can be extended at the end of the frame, a board pivoted on the said section between its ends so as to fold from a position over a mattress on the frame to a position to form an end board for the frame, and means for temporarily holding the board in either of its positions.

In testimony whereof, I have hereunto set my hand at San Francisco, California, this 16th day of January, 1919.

RALPH B. HOSNER.
